UNITED STATES PATENT OFFICE

ALFRED A. DENNIS, OF GRAND RAPIDS, MICHIGAN

TAPE GLUING MACHINE

Application filed February 19, 1929. Serial No. 341,203.

This invention relates to a tape gluing machine for the purpose of applying glue to a narrow tape which is used in connecting veneers together, the veneers being located 5 in the same plane with edges abutting and the tape overlapping the joint and gluing to the veneers at both sides of said joint.

The present invention is directed to a practical and serviceable machine which 10 may be used to apply the proper amount of glue to the tape when the tape is being applied to the veneers, or which can also be used in providing a preferred kind of tape for use for such purpose consisting of two 15 very thin narrow lengths of tape material, which is usually paper, and gluing the same inseparably together to be afterward run through the machine in the process of applying the tape to the veneers.

20 The invention is fully described in the following description and illustrated in the accompanying drawings, in which,

Fig. 1 is a vertical section through the tape gluing machine of my invention.

25 Fig. 2 is a transverse vertical section substantially on the plane of line 2—2 of Fig. 1.

Fig. 3 is a like section substantially on the plane of line 3—3 of Fig. 1.

Fig. 4 is a side elevation of the machine, 30 the same being used in gluing two tape members together.

Fig. 5 is a similar side elevation illustrating the use of the machine in applying tape to veneer, and,

35 Fig. 6 is a fragmentary side elevation of the upper part of the machine enlarged to better illustrate the construction.

Like reference characters refer to like 40 parts in the different figures of the drawings.

The machine includes in its construction a glue holding receptacle 1 which is designed to be placed above a heater, indicated at 2, for maintaining the glue 3 which is held in 45 the receptacle 1 in proper heated condition.

A grooved roller 4 is mounted in the receptacle 1 for rotation, being supported by suitable spaced uprights 5, whereby the roller is immersed at its lower portion in the glue.

50 A housing 6 is located above the receptacle

1 and at one side extends beyond it, thereby providing an opening 7 for the passage of the tape from the machine after the glue has been applied thereto. Within the housing 6 a gluing roller is located which, in practice, is made up of two spaced apart disks 8 between which a suitable fabric roller 9, preferably of felt or cloth is positioned, the disks being connected to the ends and the felt being located around a central sleeve 10. This roller lies above and to one side of the transfer roller 4 by means of which glue is transferred from the receptacle 1 to the felt 9.

The gluing roller is mounted for free rotation on a stud shaft 11, from which it may be readily removed when desired. A rod 12 is carried by one side of the casing on which an arm 13 is pivotally mounted at one end, the shaft 11 being connected to and extending laterally from the other and free end of the arm 13. The lower edge of the arm 13 is cut at an angle as at 14 (see Fig. 3) and an adjusting screw 15 having a tapered inner end threads through a side of the housing 6, the tapered end of the screw bearing against the inclined lower edge of the arm 13. The screw 15 carries a ratchet wheel 16 and an outwardly extending operating handle 17, by means of which it may be turned, a spring 16a engaging with the ratchet wheel to hold the screw in any position to which it may be adjusted.

The housing 6, preferably, is made of two parts, as shown in Figs. 2 and 3, one of the same being hingedly mounted at 18 on a side of the receptacle 1 so that it may be turned to uncover the gluing roller which may be removed from the shaft 11 at night during the time that the machine is not in operation. It is intended that the gluing roller, when not in use shall be kept immersed in water, whereby the felt or fabric 9 will always contain a considerable amount of water so that the glue when applied to the outside is kept soft and will not harden thereon. Also the water carrying felt or fabric 9 of the roller may be used as a means of applying moisture to gummed tape which is used to a large extent in veneer work and

otherwise. By proper adjustment of the screw 15 the gluing roller may be brought into more or less intimate engagement with the transfer roller 4, and the amount of glue transferred from the roller 4 to the gluing roller controlled in accordance with the extent of the contact of the gluing roller with the transfer roller, as is evident.

A curved slot 19 is cut in a side of the housing 6 thru which a curved shoe 20 of metal, lying over and spaced a short distance from the gluing roller, extends, an arm 21 formed integral with the shoe 20 passes through the slot 19 and is then turned substantially at right angles alongside of the housing 6, being mounted on a threaded stud 22 fixed to and projecting from said side of the housing, and receives a wing nut 22a whereby the shoe may be adjusted to different positions with respect to the gluing roller and firmly clamped in any position to which it has been adjusted. The slot 19 is covered by an arc shaped guarding plate 23, having a slot through which the arm 21 passes, said plate also having an arm 24 extending therefrom which is likewise mounted on the stud 22, previously described, as shown in Fig. 2.

A tape roll holding rack 25 is carried by a vertical post 26 which in turn is secured to the housing of the machine as shown in Figs. 4 and 5, the roll 27 carried by the holder thus being located above the machine. The tape is carried over a guide roller 25a on the roll holder and thence downwardly around a suitable rod or other roller 28 located at the upper end and to one side of the glue receptacle 1, through a slot in the housing of the machine, as shown in Fig. 1, over the rod 12 and thence over the shoe 20. After it passes over the shoe 20 it is carried downwardly to the lower edge of the housing at one side of the opening 7, as shown in Fig. 1, one side of the paper contacting with the fabric 9 of the glue roller, as shown. The extent to which the paper will contact with the roller is governed by the position of shoe 20, it being evident that by moving the shoe to the right (referring to Fig. 1) a greater contact of the paper with the glue roller will be had. Also in threading the paper through the machine the shoe may be adjusted far enough to one side that the tape will not contact with the roller during the process of threading. Preferably, the roll 27 of the paper tape is acted upon by a pivotally mounted retarding device 29 which is gravity operated by a weight 30 to hold the paper against aimless unwinding and to apply a suitable tension thereon which keeps the paper sufficiently taut as it is passed through the machine.

The tape with the glue applied at one side leaves the machine and is carried directly to

the veneers 31 which are passed over a table 32 between rollers 33, one of which is a driven roller, the tape lying between the upper roller and the upper side of the veneers. The tape covers the joint between the contacting edges of any two veneers and each side of the veneers some little distance beyond the joint. Ordinarily the tape is from $\frac{3}{4}$ of an inch to an inch in width and is firmly glued to the adjacent veneers holding them in close contact so that the same may be properly laid upon a core when they are to be used.

In the ordinary practice of laying and gluing veneers to a core, the same are laid with the tape side out. This method of laying veneers is open to objections in that after the veneers are laid and properly glued to the core the veneers must be finished on their outer sides to remove the tape which is thereafter of no use. The work of removing the tape and sanding and finishing the veneers is considerable. The most important objection, however, is that the moisture from the glue used in laying the veneers on the core, being absorbed by the veneers at the joint, swells the same and upon shrinkage thereafter the joint is liable to open a small amount which is very objectionable in the finished product.

It has been found practical and necessary to use a paper tape, the paper being what is known as 40 pound paper. If the veneers are laid with the paper inside, that is, between the core and the veneers to obviate the objection noted, it has been found that the paper will separate between its upper and lower sides, that is, will divide or split, whereupon at the joints the veneers are not securely connected to the core.

It is one object and purpose of my invention to utilize the machine described for making a tape which will obviate the several objections noted, and which may be used between the veneers and the core without the danger of splitting. In Fig. 4 the machine is shown as gluing the lower side of a length of tape 27 while a second length of tape 27a is carried on a second roll holder 25 mounted on the machine by a suitable horizontal support 34. The two rolls of tape 27 and 27a are in the same vertical plane and are fed between rollers 35, the upper of which is a driven roller, so that the upper tape 27 with glue applied thereto on its lower side is brought into immediate and intimate contact with the lower tape 27a and the two thus glued together rolled into a roll 36.

The rollers 35 preferably are both knurled at their outer surfaces and are pressed toward each other with considerable force so that the glue penetrates the fibers of the paper and the knurls perforate the paper to a considerable extent insuring a very intimate

gluing engagement of the two lengths of paper, while the perforations are very helpful when the tape is applied to the veneers in causing a better binding of the glue thereto.

5 It is of course to be understood that between the rollers 35 and the finished roll 36 of tape a suitable drier for the tape may be interposed if it is necessary or desirable. Also in laying the tape on veneers, as indicated 10 in Fig. 5, I have found it very desirable to direct air against the glued side of the tape. The air is projected from a nozzle 37 and the amount is controlled by a valve 38, it being evident that the glue may be more or 15 less dried and thickened in accordance with the amount of air that is directed against it thereby compensating for different consistencies of glue used and variations in thickness or body thereof.

20 I have found that in this manner two rolls of very thin paper, known to the trade as 15 pound tissue kraft paper, may be used to provide a suitable tape for veneers and the roll 36 of tape impregnated with glue may 25 then be laid between two adjoining veneers by use of the machine, as shown in Fig. 5, glued to the veneers, and that veneers glued together with a two ply glued tape of the character described may be laid with the 30 tape inside or between the veneers and core, and the tape is not susceptible to separation or splitting as is a heavier single thickness of paper tape.

The mechanism described is very practical and serviceable and has so proved in actual practice. Many variations in structural detail may be resorted to without departing from the invention which is defined in the appended claims and my invention, accordingly, is to be considered comprehensive of all forms of structure coming within the scope of said claims.

I claim:

1. In a machine of the class described, a 45 glue holding receptacle, a transfer roller rotatably mounted therein, a housing above the receptacle, an arm pivotally mounted at one end at the inner side of said receptacle, a gluing roller rotatably mounted within said 50 housing at the other end of the arm, said arm at its lower edge having a downwardly and inwardly inclined cam surface, a screw having a tapered end threaded through a side of the housing, said tapered end engaging with said cam surface of the arm, a sheet metal shoe located over said roller, an arm extending from said shoe through a side of the housing, said side of the housing having an arc shaped slot to pass said 55 arm, said arm being turned downwardly after passing through said slot, means for pivotally mounting said arm at its lower end on said housing, means for securing said arm and shoe in any position to which moved, and means for drawing a continuous 60

length of tape through said housing over said shoe and bringing the tape at one side in contact with the gluing roller, the extent of contact being determined by the position of the shoe with respect to the roller.

2. In a machine of the class described, a 70 glue holding receptacle, a transfer roller rotatably mounted therein, a housing above the receptacle, an arm pivotally mounted at one end at the inner side of said receptacle, a gluing roller rotatably mounted within said 75 housing at the other end of the arm, said arm at its lower edge having a downwardly and inwardly inclined cam surface, a screw having a tapered end threaded through a side of the housing, said tapered end engaging with said cam surface of the arm, and means for drawing a continuous length of tape through said housing and bringing the tape at one side in contact with the gluing roller.

3. In a tape gluing machine having a 80 receptacle for holding glue, the combination of, a transfer roller revolvably mounted therein, a gluing roller mounted above the transfer roller adapted to contact therewith, a shoe located over the gluing roller, means for adjusting the shoe to three or more different positions, and means for guiding tape to and over said shoe and into contact 85 engagement with one side of the gluing roller, the extent of contact of the tape with the gluing roller being governed by the position of said shoe.

4. A machine of the class described, comprising a glue holding receptacle having a portion extending upwardly, a transfer roller rotatably mounted therein, a housing hinged to and extending over the receptacle, 100 an arm pivotally mounted on said upwardly extending portion, a gluing roller mounted on the arm and located above and adapted to contact with the transfer roller, means for guiding a continuous length of tape through said housing over the gluing roller, whereby 105 the tape at one side contacts with said gluing roller, and adjustable means mounted between the gluing roller and tape and over which the tape passes for governing the extent of contact of the tape with said gluing roller.

5. A machine of the class described, comprising a glue holding receptacle, a housing hinged to and covering said receptacle, a 110 gluing roller rotatably mounted in said receptacle, means to transfer glue from said receptacle to said gluing roller, means for guiding a continuous length of tape through said housing and over the gluing roller, whereby the tape contacts at one side with said roller, and adjustable means mounted on said housing and interposed between the roller and the tape over which the tape passes for controlling the extent of contact of the 115 tape with said roller.

6. In a construction of the class described, a glue holding receptacle, a cover thereover, an arm mounted at the inner side of said receptacle, a stud shaft extending from the arm, a gluing roller removably mounted on said stud shaft, means for transferring glue from the receptacle to said roller, means for guiding a continuous length of tape through said receptacle and over said roller to contact therewith at one side of the tape, and adjustable means mounted between the tape and the roller over which the tape passes for shifting the tape toward or away from the roller to govern the extent of contact therewith.

10 7. A construction containing the elements in combination defined in claim 6, combined with means for readily opening said housing whereby the roller may be removed from said stud shaft when not in use.

15 In testimony whereof I affix my signature.
ALFRED A. DENNIS.
